ABSTRACT: A machine for assembling open-topped wirebound boxes of the type having solid wooden box ends with a wirebound mat stapled to the front and rear edges thereof, including means for feeding the box ends into clamps on an elevator in its lower rest position, feeding the mat above the box ends, raising the elevator to cause the ends to engage the mat and push it past a mat-folding station then through a series of dwell positions at which staples are driven at spaced positions in each of the four corners, with means at the uppermost position to grip the completed box and support it at the bottom of a vertical stack, and with pusher means to push the top box in the stack out of the machine.

BOX-ASSEMBLING MACHINE

This invention relates to a machine for assembling wirebound "flats"—that is, open-topped wirebound boxes of the general type disclosed, for example, in U.S. Pat. No. 3,506,179 issued on Apr. 14, 1970.

Such boxes (which term is used herein to include crates and other containers) have one-piece wooden rectangular box ends with a wirebound mat folded around the front, bottom and rear sides of the box ends and secured thereto by staples driven through the face material of the front and rear side sections of the mat and into the underlying edges of the box ends.

The present invention provides a practical automatic mechanism for properly assembling the box ends and mat and securing them together by driving staples at the proper positions, this mechanism being simple and inexpensive in construction, rapid and reliable in operation, and susceptible of ready adjustment and simple maintenance.

In the drawings:

FIG. 1 is a perspective view of an illustrative machine embodying features of the present invention.

FIGS. 2A, 2B and 2C are fragmentary vertical and longitudinal sectional views of adjacent sections of the machine taken along the line 2-2 of FIG. 1. Placed side by side, in order from FIG. 2A at the left to FIG. 2C at the right, they form a composite sectional view of substantially the complete machine.

FIG. 3 is an end elevation of the machine as viewed from the input end, which appears at the left in FIGS. 1 and 2A.

FIG. 4 is an enlarged, fragmentary, horizontal section taken on the line 4-4 of FIG. 2A.

FIGS. 5 and 6 are fragmentary vertical and transverse sections taken respectively on the lines 5-5 and 6-6 of FIG. 4.

FIG. 7 is an enlarged, fragmentary horizontal section taken on the line 7-7 of FIG. 2B.

FIG. 8 is a vertical and transverse section taken on the line 8-8 of FIG. 7.

FIGS. 9A and 9B are fragmentary vertical and transverse sectional views of adjacent and slightly overlapping portions of the machine taken on the line 9-9 of FIG. 2C.

FIG. 10 is an enlarged fragmentary vertical and longitudinal section taken on the line 10-10 of FIG. 9A.

FIGS. 11A and 11B are horizontal sectional views of adjacent and slightly overlapping portions of the machine taken respectively on the line 11A-11A of FIG. 2B and on the line 11B-11B of FIG. 2C.

FIG. 12 is an enlarged fragmentary vertical and longitudinal section taken on the line 12-12 of FIG. 11A.

FIGS. 13, 14 and 15 are fragmentary horizontal sections taken respectively on the lines 13-13, 14-14 and 15-15 of FIG. 12.

FIG. 16 is a fragmentary vertical and transverse section taken on the line 16-16 of FIG. 11A.

FIG. 17 is a vertical and longitudinal section taken on the line 17-17 of FIG. 16, which, like FIGS. 12-15, shows the stapling mechanism at the start of the staple-driving stroke.

FIG. 18 is a horizontal section taken on the line 18-18 of FIG. 17.

FIG. 19 is a view similar to FIG. 18 but showing the stapling mechanism at the finish of the staple-driving stroke.

FIG. 20 is a fragmentary horizontal section taken on the line 20-20 of FIGS. 2B and 2C.

FIG. 21 is a fragmentary vertical and longitudinal section taken on the line 21-21 of FIG. 9B.

FIGS. 22 and 23 are fragmentary vertical and longitudinal sections taken respectively on the lines 22-22 and 23-23 of FIG. 20.

FIG. 24 is a schematic diagram of the electrical control circuit of the machine.

GENERAL ORGANIZATION

As best shown in FIG. 1, the machine is supported on a frame which includes four short vertical posts 30 arranged at the corners of a rectangle at the front portion of the machine (the left-hand portion as viewed in FIG. 1), four longer vertical posts 32 similarly arranged at the rear (right-hand) portion, horizontal side rails 34 extending the length of the machine and attached to the posts 30 and 32, intermediate horizontal channel member 36 and upper horizontal angle members 38 attached to the posts 32. A transverse angle member 40 extends between the posts 30 at the front end of the machine and transverse rails 42 extending horizontal between the posts 32.

At the front end of the machine a pair of box end hoppers 44 are supported on brackets 46 secured to the upper ends of the posts 30, the hoppers 44 being inwardly open channels positioned generally vertically, but tilted slightly outwardly at their upper ends to support and laterally confine stacks of box ends E. Individual box ends are stripped simultaneously from the two hoppers and fed between open clamp members of an elevator assembly in the box assembly station by box end conveyor chains 48 which are driven continuously by a motor 50. Meantime, the operator will have placed a wirebound mat M on a supporting table 52 supported at the right-hand side of the machine by legs 54 whose lower ends are attached to a base plate 56. A pair of feed fingers 58 at the outer end of the table 52 actuated by a cam 60 driven by the motor 50 in synchronism with the conveyor chains 48 engage the outer end of the mat M and push its inner end into the nip of feed rollers 62 driven continuously by a motor 64 and spring loaded idler rollers 66, and these rollers feed the mat M inwardly above the paths of the box ends E. Then the elevator assembly is raised by a cam-actuated toggle assembly driven by the motor 50. As the elevator moves away from its lower starting position, the clamp members are cam actuated to grip the box ends and hold them securely in place. As the box ends are driven upwardly by the elevator, they engage the under side of the bottom section of the mat M and push it upwardly past mat-bending elements which engage the outwardly projecting front and rear side sections of the mat and fold them around the front and rear edges of the box ends. The assembled box parts are then moved stepwise to a succession of three dwell positions in a stapling station at which four stapling mechanism 68 one located at each corner, drive a succession of three staples at spaced positions through each end of the front and rear side sections of the mat and into the underlying edges of the box ends.

As the box moves to the uppermost of these three dwell positions, it passes between a pair of pawl members which engage the ends of the box and support it after the elevator descends to its starting position for the next cycle. A stack of several completed boxes is formed at the top of the machine, with each box as it moves upwardly to the final dwell position lifting and supporting the boxes above it in the stack. Once each cycle, the uppermost box in the stack is pushed laterally out of the machine by radial pusher arms 70 on an intermittently rotating shaft 72.

BOX END FEEDING

The box end feeding mechanism is shown in FIGS. 2A, 2B, 4, 5, 6, 7 and 8. As may be seen in FIGS. 2A and 2B, the conveyor chains 48 are trained about upper and lower front idler sprockets 74 and 76, upper rear idler sprockets 78 and drive sprockets 80 (FIG. 2B). The drive sprockets 80 are keyed on the main drive shaft 82 which is rotatably supported in bearings 84 secured to the lower edges of the side rails 34. As may be seen in FIGS. 1 and 20, the drive shaft 82 is driven by the motor 50 through variable speed pulley 86 (FIG. 1), belt 88, pulley 90, shaft 91, speed reducer 92, sprocket 94, chain 96 and sprocket 98 fixed on the drive shaft 82. A solenoid-actuated brake 99 (FIG. 20) engages the shaft 91 to stop the drive train quickly when the motor 50 is switched off.

The upper rear idler sprockets 78 are rotatably mounted on a shaft 100 (FIG. 2B) which rests upon extensions 102a at the ends of rocker arms 102 pivotally mounted on bolts 101 secured to the inner faces of a supporting bar 123 whose front end is supported by a spacer block 132 (FIG. 2A) on the transverse angle member 40 and whose rear end is similarly supported on another transverse angle member 134 (FIG. 2B) secured to the front pair of taller posts 32. The position of the shaft 100 on the extensions 102a is adjusted by means of bolts 107 threaded into the ends of the rocker arms 102 and secured by lock nuts 105. The rocker arms 102 are urged in a counterclockwise direction, as viewed in FIG. 2B, by means of tension springs 104 connected at their upper ends to a rod 106 which extends between the front ends of the rocker arms 102 and at their lower ends to eye bolts 103 secured to brackets 108 on the posts 32. Counterclockwise movement of the rocker arms 102 by the springs 104 is limited by engagement of the left-hand ends of the arms 102 with stop bolts 109 (FIG. 2B) adjustably threaded through brackets 110 secured to transverse angle member 134 and fixed by locknuts 111.

In the event of a blockage in the feeding of the box ends, the resulting increase of tension on either of the chains 48 pivots the rocker arm 102 in a clockwise direction, against the resistance of the springs 104, causing the rod 106 to press upwardly against the front end of a lever 113 (FIG. 2B) which is pivoted at 113a on a bracket 115 and whose rear end bears on the plunger of a stop switch 117. Thus, as explained more fully hereinafter in connection with the circuit diagram, FIG. 24, the jamming of either of the chains 48 will stop the main drive motor 50 to prevent damage to the machine.

As shown in FIGS. 2A and 3, the upper front idler sprockets 74 are rotatably supported on a transverse shaft 112 extending between the front posts 30, while the lower front idler sprockets 76 are rotatably supported on a transverse shaft 114 secured by bolts 119 at the lower ends of rocker arms 116 pivoted on the shaft 112. The rocker arms 116 are urged in a clockwise direction by tension springs 118 fastened at one end to pins 120 at the upper ends of the arms 116 and at the other end to eye bolts 121 (FIG. 1) connected to the rear-mounting brackets 46.

The front portion of the upper span of each of the chains 48 normally slides along a horizontal guide rail 122 (FIGS. 6 and 8) secured to the upper face of the supporting bar 123. Mounted at spaced intervals on each of the chains 48 is a series of stripper blocks 124 which project outwardly at each side of the chain in position to engage cam plates 126 (FIGS. 2A and 5) secured to opposite sides of the supporting bar 123 beneath the front end of the hopper 44.

As the stripper blocks 124 approach the front end of the hopper, they are cammed upwardly by the cam plates 126 to the position shown in FIGS. 2A and 5, with the rocker arms 116 pivoting counterclockwise, as viewed in FIG. 2A, against the resistance of the springs 118 to allow the chains 48 to be pulled upwardly to accommodate this upward movement of the stripper blocks. Since the springs 118 are not as stiff as the springs 104 (FIG. 2B), the pulling of the chains 48 due to lifting of the stripper blocks 124 by the cam plates 126 does not cause pivoting of the rocker arms 102 (FIG. 2B) with resulting actuation of the stop switch 117. Any excessive tension imposed on the chains 48 due to a malfunction in the feeding of box ends will of course occur in the portion of the chains from the drive sprockets 80 back to the hoppers 44, so that such tension will not cause stretching of the weaker springs 118 but only of the stronger springs 104, thus actuating the stop switch 117 to stop the chains 48.

As best shown in FIG. 4, the stack of box ends E in each of the hoppers is supported at its outer front corners on a pin 125 extending inwardly from the front hopper mounting bracket 46, and at its outside rear corner of a block 127 secured to the rear hopper mounting bracket 46.

The inner edge of the stack rests on a plate 128 extending horizontally outwardly from the upper edges of a pair of mounting blocks 130 (FIG. 2A) secured to the inner face of

the supporting bar 123. The inside lower edge of the stack is laterally confined by a pair of angle members 138 secured to the top of the plate 128 and projecting upwardly therefrom.

The bottom box end in the hopper is supported at such a level that as each stripper block 124 rides upwardly over the cam plates 126, a beveled surface at the upper leading corner of the stripper block engages the lower trailing corner of the bottom box end and cams it slightly upwardly (lifting the front end of the stack above it) to insure positive engagement between the stripper block and the bottom box end. A finger 124a projecting upwardly from the trailing end of the stripper block a distance slightly less than the thickness of a box end engages the trailing end of the bottom box end and pushes the box end out of the rear end of the hopper. As shown in FIGS. 2A, 4 and 5, at the rear end of the hopper 44, an exit gate 140 is pivotally mounted on a bolt 142 threaded into a tab 143 on the rear bracket 46. A finger 145 projects downwardly from the exit gate 140 with its lower edge above the bottom box end E in the hopper, but opposite the leading ends of the several box ends above it in the stack to prevent such box ends from moving out of the hopper due to friction with the bottom box end as it is stripped off the stack. The exit gate 140 is urged in a clockwise direction, as viewed in FIG. 4, about the pivot bolt 142 by means of a tension spring 144 connected at one end to a bolt 146 at the outer end of the exit gate and at the other end to an eye bolt 148 fastened to a bracket 150 on the transverse angle member 40. Clockwise movement of the exit gate 140 by the spring 144 is limited by a stopscrew 152 which is adjustably threaded through the exit gate 140 and fixed by a locknut 154, and which engages a tab 156 projecting upwardly from the plate 128. In the event of a jam or other malfunction which results in one or more box ends being wedged between the moving chain 48 and the exit gate 140, the gate can open to allow the misaligned box ends to leave the hopper and clear the jam.

As best shown in FIG. 3, the two exit gates 140 at opposite sides of the machine each have fixed at their free inner ends extension arms 153 which overlap at the center of the machine, with the extension arm 153 on the left-hand exit gate 140 being located behind the extension arm on the right-hand exit gate, so that the right-hand gate is held closed by the same tension spring 144 which serves the left-hand gate. As shown in FIGS. 3 and 4, arranged to bear against the left-hand extension arm 140 is the spring-loaded actuating finger 155a of an open-gate stop switch 155 mounted on a bracket 157. When the exit gates 140 are in normal, closed position, the switch 155 is held closed. Opening of either exit gate allows the spring-loaded actuating finger 155a to move rearwardly, actuating the switch 155 and, as explained more fully hereinafter in connection with the circuit diagram, Exhibit 24, this stops the drive motor 50 to prevent any possible damage to the machine due to jamming of the box-end feeding mechanism.

The spacing of the stripper elements 124 along the length of the chain and the velocity of the chains are such that one box end E is stripped off the bottom of each hopper for each box assembling cycle of the machine. As best shown in FIG. 5, as each box end leaves the hopper, its inner edge is supported on the plate 128 but its outer edge is unsupported, so that it tips downwardly, the box end rotating through an angle of roughly 90° to a generally vertical position in which its lower edge rides upon a guide rail 158 (FIG. 6) secured to the supporting bar 123 and projecting horizontally outwardly therefrom. A flared guide plate 159 (FIG. 4) extending upwardly from the outer edge of the guide rail 158 guides the leading end of the box end of the box end inwardly onto the guide rail 158 and a series of three inclined guide ribs 160, 162 and 164 (FIGS. 4 and 6) break the fall of the box end and cause it to slide gradually downward into the proper position on the guide rail 158. As the box end thus rotates, it moves out of the path of the stripper elements 124, and will remain stationary on the guide rail 158 until it is engaged by the next of a series of pusher elements 166 which are mounted at spaced positions on the top of each of the conveyor chains 48.

These pusher elements 166 project outwardly to engage the trailing end of the box end E and push it along the guide rail 158, with the box end guided laterally between an inner side rail 168 (FIG. 6) forming an effective extension of the outer cam plate 126 and by the guide plate 159. As the box ends E are thus conveyed, their leading ends engage a cam surface 170a (FIG. 7) at the front end of a guide bar 170, camming the box ends inwardly into the space between the guide bar 170 and the side rail 168, which is just wide enough to accommodate the thickness of a box end, thus laterally positioning the box ends precisely for feeding them endwise into the holding means on the elevator assembly. The movement of the box end by the pusher element 166 automatically stops as the chain 48 rotates clockwise around the upper rear sprocket 78 through a 90° angle to the point shown in FIGS. 2B and 7 at which the movement of the pusher element loses all its horizontal component and follows a straight downward path.

BOX END HOLDING

As shown in FIGS. 7 and 16, as the box ends near the end of their horizontal movement, they slide along the top of a supporting plate 163 fixed on the frame of the machine and between a fixed vertical inner guide plate 165 and an outer movable presser bar 167 supported at the upper ends of leaf springs 169 (FIG. 16) whose lower ends are fixed to the supporting plate 163 by screws 171. As shown in full lines in FIG. 16, the springs 169 normally hold the presser bar spaced from the guide plate 165 a distance less than the thickness of the box ends, but, as shown in FIG. 7, the front end of the presser bar 167 is flared outwardly so that the leading edge of the box end will cam it outwardly against the resistance of the springs 169, as shown in broken lines in FIG. 16, and cause the box end to be gripped and held in proper position to be engaged by the elevator assembly.

As shown in FIGS. 9A and 16, the inner edges of the vertical members 172 of the elevator assembly are provided with shoulders 172a which, as the elevator assembly moves upwardly, engage the lower edges of the box ends, stripping them from the frictional grip of the presser bars 167 and raising them with the elevator assembly. After the box ends have been thus engaged by the shoulders 172 and thereby properly aligned horizontally, the box ends are gripped between the inner edges of the vertical members 172 and clamp arms 174 fixed on and extending upwardly from a horizontal rock shaft 176 journaled at its ends in the front and rear horizontal members 178 of the elevator assembly.

The clamp arms 174 are urged outwardly toward box-end clamping position, in which they are shown in broken lines in FIG. 9A, by a tension spring 180 connected between the lower end portions of a pair of depending crank arms 192 whose upper ends are fixed to the two rock shafts 176 at opposite sides of the elevator assembly. At the starting position of the elevator assembly, which is the lowest position of its vertical reciprocatory movement, the clamp arms 174 are held against the resistance of the spring 180, in the open position, out of engagement with the box ends E, as shown at full lines in FIG. 9A, by rollers 184 at the ends of outward extensions 182a at the lower ends of the crank arms 182 engaging horizontal cam plates 186 extending inwardly from the lower ends of supporting bars 187 (see also FIG. 2C) secured to the side plates 34. As the elevator assembly is moved away from this starting position the rollers 184 move up off the cam plates 186, allowing the spring 180 to move the clamp arms outwardly to clamp the box ends firmly against the inner edges of the vertical members 172, as shown in broken lines in FIG. 9A. As may be seen in FIGS. 9A and 16, the upper portions 172b of the inner edges of the vertical members and the opposed surfaces of the clamp arms 174 are so shaped that the box ends E are tilted slightly outwardly at the upper edges, which will become their lower edges in the completed box, since the boxes are assembled in inverted position.

ELEVATOR GUIDING AND DRIVING

The elevator assembly is guided laterally during its vertical reciprocatory movement by engagement of the transverse faces of each of the four vertical members 172 with a pair of vertically spaced rollers 188 (FIGS. 2C and 9A) rotatably mounted on bolts 190 extending through the upper and lower ends of a mounting plate 192 secured to the inner face of the side rail 34, and by engagement of the outer edges of each of the vertical members 172 with a roller 194 rotatably mounted on a bolt 196 extending through the central portion of the mounting plate 192.

The elevator assembly is urged toward its lowermost or starting position by gravity, and is driven upwardly by means of a cam 198 (FIGS. 2B and 20) fixed on the main drive shaft 82 and engaged by a cam follower roller 200 (FIG. 2B) rotatably mounted between the rear end portions of a pair of arms 202 of a toggle assembly, the other end of the arms 202 being connected, as shown in FIG. 2A, to a block 203 fixed on a transverse shaft 204 journaled in bearings 206 secured to a transverse angle member 208 whose opposite ends are connected to the rear pair of shorter posts 30. The rear ends of the arms 202 are pivotally connected by a bolt 210 to the front ends of a pair of arms 211 of the toggle assembly, whose rear ends are connected to a block 214 (FIGS. 2C and 9A) rotatably supported at the center transverse shaft 216. The ends of the shaft 216 are pivotally connected to the lower ends of turnbuckle links 218 whose upper ends are pivotally connected to a rod 220 which extends between cross bars 222 connected to the lower ends of the vertical members 172 at each side of the elevator assembly. The shaft 216 is maintained at a fixed spacing from the shaft 204 (FIG. 2A) by a pair of radius arms 224 whose opposite ends are respectively pivotally connected to the shafts 204 and 216.

The cam 198 rotates with the main drive shaft one revolution for each box assembly cycle, with the roller 200 being held against the cam surface by the weight of the elevator and toggle assemblies, so that the roller and the rear end of the toggle arms 202 move vertically in accordance with shape of the cam, with resulting vertical movement of the arms 212, the turnbuckle links 218 and the elevator assembly. As previously mentioned, the cam 198 is shaped to move the box ends E upwardly from the starting position in a series of steps with three intervening dwell positions at which the box parts are presented for the driving of staples at properly spaced positions at each vertical corner of the box.

MAT FEEDING

As the elevator assembly starts upwardly toward the first of such dwell positions, the box ends are first tightly clamped in the clamping means, as described above, then the upper edges of the box ends engage the under surface of the bottom section of a wirebound mat M which has previously been fed into the machine by the mat feeding mechanism shown in FIGS. 9B and 21. As previously mentioned, this mechanism includes a table 52 supported at the right-hand side of the machine on legs 54 extending upwardly from a base 56. During each operating cycle of the machine, the operator manually places a mat M face downwardly on the table, within the properly positioned laterally by the side rails 52a and end rail 52b, where the mat rests until its outer edge is engaged by feed fingers 58 fixed to and extending upwardly from a rock shaft 226 whose ends are rotatably supported in bearings 228 secured to the legs 54. The feed fingers 58 are urged in a counter-clockwise direction, as viewed in FIG. 9B, by a tension spring 230 connected at one end to a crank arm 232 fixed on the rock shaft 226 and at the opposite end to an eye bolt 234 secured to a tab 236 on a bracket 238 projecting outwardly from a mounting plate 240 secured to the side rail 34. However, the feed fingers 58 are normally held against the resistance of the spring in an outer, retracted position, in which they are shown in full lines in FIG. 9B, by a cable 242, one end

of which is connected to the lower end of the crank arm 232 and which extends inwardly over a pulley 244 rotatably supported on a bolt 246 at the outer end of the bracket 238 and downwardly where its opposite end is connected to a bolt 248 at the rear end of a lever 250. The lever 250 is pivoted on a bolt 252 threaded into a bracket 254 extending outwardly from the side rail 34, and has rotatably mounted at its front end a cam follower roller 256 which, as shown in FIG. 21, bears on the surface of the aforementioned cam 60 secured at the outer end of the main drive shaft 82. The roller 256 is maintained in contact with the surface of the cam 60 by the spring 230 which urges the crank arm 232 and rock shaft 226 counterclockwise and pulls the cable 242 outwardly and the rear end of the lever 250 upwardly. During each box assembly cycle, the cam 60 makes one revolution, causing the roller 256 to ride into a steep drop 60a in the cam surface, abruptly relaxing the cable 242 and allowing the spring 230 to pull the feed fingers 58 quickly inward to strike the outer end of the mat M on the table 52. This kicks the mat M inwardly so that its inner end, guided by an upwardly flared guide plate 257 (see also FIG. 9A) enters the nip of a pair of lower-driven rollers 62 with a pair of upper idler rollers 66. The idler rollers 66 are rotatably mounted on bolts 258 at opposite ends of a horizontal bar 260 which is supported at the lower end of an arm 261 extending downwardly from the horizontal channel member 36, by means of a bolt 262 which extends loosely through a vertical slot 261a in the arm 261, thus permitting vertical movement of the idler rollers 66 toward and away from the driven rollers 62. A leaf spring 263, whose central portion bears against the arm 261 and whose ends press downwardly on the upper face of the bar 260, urges the idler rollers downwardly toward the driven rollers.

The driven rollers 62 are fixed on a shaft 264 rotatably supported in bearings 266 mounted on brackets 268 projecting upwardly from the side rail 34. As previously mentioned, the shaft 264 is driven by a motor 64. A friction drive is provided by mounting the motor 64 on a supporting frame 270 which is pivotally mounted at its lower end on a shaft 272 supported on arms 274 extending outwardly from the side rail 34 and which is urged in a counterclockwise direction, as viewed in FIG. 9B, by a tension spring 276 connected at one end to the frame 270 and at the other end to an eye bolt 278 connected to the side rail 34. Thus urges a roller 280 fixed on the drive shaft of the motor 64 into frictional engagement with a larger roller 282 fixed on the shaft 264, resulting in continuous frictional driving of the driven rollers 282. As the leading end of each mat reaches the nip of the rollers 62 and 66, it is gripped by the rapidly rotating rollers and thrown endwise across the machine to the point where its leading edge strikes the upwardly projecting ends 172b (FIG. 9A) of the vertical members 172 at the far side of the elevator assembly. This stops the transverse movement of the mat and allows it to fall to rest on a pair of ramp plates 284 (FIGS. 2C, 9A and 10) mounted at the upper ends of vertical arms 286 whose lower ends are supported on transverse angle members 288 (FIG. 2C) fixed at their opposite ends on the side rails 34. As best shown in FIG. 9A the ramp plates 284 are inclined to engage the leading edge of the mat and guide it upwardly above the upper edge of the box end E which is simultaneously being fed into the spring-loaded holding means at the far side of the elevator assembly. However, the trailing edge of the mat is allowed to drop downwardly behind the inner edges of the vertical members 172 at the near side of the elevator assembly, thus preventing rebounding of the mat when its leading edge strikes the vertical members 172 at the far side, and insuring proper positioning of the mat transversely of the machine. The front and rear side sections F and R, respectively, of the mat project forwardly and rearwardly beyond the ramp plates 284 and are supported on flanges 290 (FIGS. 9A and 10) projecting inwardly at the lower ends of support arms 292 fixed on rock shafts 294 rotatably supported in bearings 296 secured to the underside of the channel members 36.

MAT FOLDING

As previously mentioned, after the mat M has thus been fed into proper position onto the ramp plates 284 in the path of the elevator assembly, the elevator assembly is raised to a series of three dwell positions at the stapling station. During this upward movement to the first of these dwell positions, the box ends E, having been stripped from the spring-loaded holding means and firmly gripped in proper position by the clamping means, are raised to cause their upper edge to engage the opposite edges of the underside of the bottom section B of the mat M which is resting on the ramp plates 284, lifting the mat. The inclined inner edges 172b of the upper portions of the vertical members 172 of the elevator assembly engage the edges 15 of the mat and align them perfectly with the outer corners of the box ends. As the mat is raised by the box ends, the outwardly projecting front and rear side sections F and R engage mat folding members 298 projecting inwardly from the lower ends of the support arms 292 in the path of the outer edges of 20 the front and rear side sections. This initiates the folding of the front and rear side sections F and R around the upper corners of the box ends.

A tension spring 300 connected between the lower ends of 25 depending crank arms 302 fixed on the rock shafts 294 tends to rotate the shafts in such direction as to move the mat folding members inwardly toward the box parts. When the elevator assembly is in its lower, starting position, the mat-folding members are held against the resistance of the spring 300 in an outer, retracted position, in which they are shown in broken lines in FIG. 10, by cam plates 304 on the front and rear horizontal members 178 of the elevator assembly engaging cam follower rollers 306 rotatably mounted at the lower ends of crank arms 308 whose upper ends are supported on plates 310 fixed to the outer edges of the support arms 292. As the elevator assembly moves upwardly toward the first dwell position, the cam plates 304 move clear of the rollers 306, allowing the spring 300 to rotate the rock shafts 294 to move the mat-folding members to their inner positions, shown in full 30 lines in FIG. 10, during which movement they complete the folding of the front and rear side sections F and R of the mat down flat against the underlying edges of the box ends E. If the front and rear side sections F and R are misaligned with the bottom section B, as they are folded downwardly, their edges 45 are cammed inwardly into proper alignment by beveled cam surfaces 342a (FIGS. 11A, 11B and 16) on blocks 342 secured by bolts 344 to the vertical members of the elevator assembly.

The central portion of the relatively thin and flexible face 50 material of the front and rear side sections is supported against the inward pressure of the mat folding members by backup members 307 (FIGS. 2C, 9A and 10) fixed to and extending upwardly from the center of the horizontal members 178 of the elevator assembly.

As the elevator assembly moves upwardly to the point 55 shown in full lines in FIG. 10, the mat-folding members slide off the lower edges of the front and rear side sections of the box and the cam follower rollers 306 engage the vertical arms 286, stopping their further inward movement in the positions 60 shown in broken lines in FIG. 10, where they will be engaged by the inclined lower edges of the cam plates 304 when the elevator assembly returns toward its lowermost starting position, thus rotating the rock shafts 294 and again moving the mat-folding members 298 outwardly to their retracted position 65 shown in broken lines.

STAPLING

The four stapling mechanisms or "stitchers" which drive a 70 series of three staples through the face material of the front and rear side sections of the mat and into the underlying edge of the box end at each vertical corner of the box are generally shown in FIGS. 11A and 11B, in which they are generally designated 68, and one of these four identical units is shown in 75 greater detail in FIGS. 12 through 19.

As best shown in FIGS. 11A and 11B, these four stitchers 68 are mounted opposite the four corners of the path of the elevator assembly on mounting plates 320, each of which is supported for limited pivotal movement about a vertical shaft 322 which is journaled in brackets 324 secured to the upper and lower edges of the transverse rail 42 and which extends rotatably through openings in side plates 326 and 327 projecting outwardly from opposite edges of the mounting plates 320 (see also FIG. 12). The two mounting plates 320 at each end of the machine are urged to rotate about the shafts 322 in opposite directions so as to move the two stitchers 68 at opposite sides of the machine outwardly away from one another, by a tension spring 328 extending between eye bolts 330 connected to the outer ends of the mounting plates 320. As shown in FIG. 11B, outward movement of the stitchers by the springs 328 is limited by stop bolts 332 adjustably threaded through blocks 334 connected to the transverse rails 42 and secured by locknuts 336, with the outer ends of the stop bolts 332 bearing against the inner faces of the mounting plates 320 near their outer ends. The stop bolts 332 are adjusted so that the stitchers are normally held by the spring 328 in the position shown in FIGS. 11A and 11B, which is the proper transverse position for driving of the first staple at each corner of the assembled box parts—that is, the bottom staples in the completed box, after the box is inverted to normal position with its open side facing upwardly.

As previously mentioned, the box ends are inclined inwardly at their upper edges and, to assure that all three staples are driven in properly centered relation to the thickness of the box ends, the stitchers are moved inwardly a short distance during movement of the box parts to the second and third dwell positions. This is accomplished by cam plates 338 (FIGS. 11A, 11B and 16) secured to the outer faces of the stitchers 68 by bolts 339 (FIG. 16), the cam plates 338 being engaged by pins 340 projecting from the aforementioned blocks 342 on the vertical members 172 of the elevator assembly.

The stitchers 68 are of the general type disclosed more fully, for example, in U.S. Pat. No. 2,304,510 issued Dec. 8, 1942. They are adapted to receive a wire strand, sever short lengths from the end thereof, form these lengths into staples and drive the staples into the box parts. The staple former 346 (FIGS. 12 and 17) and driver 348 are separately driven in properly timed relation by means of eccentric cams 350 and 352 (FIG. 12), respectively, keyed on the aforementioned shaft 322. This shaft 322 has keyed at one end a miter pinion 354 which meshes with a similar pinion 356 keyed on a stitcher drive shaft 358 rotatably supported in bearings 360 secured to the blocks 334. As shown in FIGS. 2B and 2C, the two drive shafts 358 are driven by sprockets 362 (see also FIGS. 11A and 11B) keyed on the drive shafts 358 and having trained about them a chain 364 which is also trained about idler sprockets 366 and 368 (FIG. 2B) rotatably mounted on bolts 370 and 372 respectively fastened to the channel member 36 and to the lower end of a tension lever 374, and about a drive sprocket 376 fixed on a shaft 378 shown in FIGS. 2B, 22 and 23. As shown in these figures, the shaft 378 also has keyed on it a pinion 380 which meshes with an intermittent gear 382 keyed on the main drive shaft 82. To keep the pinion 380 (FIG. 22) in proper position to mesh with the intermittent gear 382 during the intervals when the toothed portion of the intermittent gear is out of engagement with the pinion 380, a locking plate 384 (FIGS. 20 and 23) also keyed on the main drive shaft 82 is provided with a concentric cylindrical surface 384a which comes into sliding engagement during such intervals with a complementary cylindrical surface 386a on a cooperating plate 386 keyed on the shaft 378.

The lever 374 (FIG. 2B) on which the idler sprocket 368 is mounted is pivotally supported on a bolt 388 fastened to the channel member 36, and is urged to rotate in a clockwise direction, as viewed in FIG. 2B, by a tension spring 390 connected between the upper end of the lever 374 and the frame of the machine. This spring 390 urges the sprocket 368 to the left, as viewed in FIG. 2B, and keeps the chain 364 under tension.

The relationship between the driven sprockets 362 and the other mechanisms driven from the main drive shaft 82 is such that the staple former 346 and driver 348 (FIG. 12) are actuated in properly timed relation to drive three staples during the three dwell periods of the elevator assembly. The sequence of operation of the staple former and driver may be better understood from a study of FIGS. 12 and 14 through 19. In FIGS. 12, 14, 15 and 19, the stapling mechanism is shown at the completion of the staple driving stroke, as the cam 352 has reached the point where its highest part is toward the stitcher, forcing the staple driver 348 inwardly to drive a staple S through the face material of the front side section F (FIG. 19) of the mat and into the underlying edge of the box end E. A compression spring 392 interposed in the stapler drive rod 394 accommodates slight variations in the width of the boxes and assures full driving of the staples S in all boxes falling within this tolerance.

As may be seen in FIGS. 14 and 15, the shaft 322 on which the eccentric cams 350 and 352 are fixed rotates in a clockwise direction and the relative orientation of the two cams is such that the cam 350 which actuates the staple former 346 leads the cam 352 which actuates the staple driver 348 by an angle of approximately 60°. Thus the staple former is reciprocated inwardly and outwardly slightly ahead of the staple driver.

As the shaft 322 continues its rotation past the point shown in FIGS. 12, 14, 15 and 19, first the staple former 346 and then the stapler driver 348 are retracted to their outer positions, as another length of wire W is fed into the stitcher preparatory to the next cycle. Then the staple former 346 is driven inwardly to the point shown in FIGS. 17 and 18, severing a piece of proper length from the end of the wire and forming it into a staple S by bending its end portion about a former bar 396, which is pivotally mounted on a pin 398 for movement between a staple-forming position, in which it is shown in FIGS. 16 and 18, and a staple driving position in which it is shown in FIG. 19. When the staple driver 348 is in its retracted position, an outer cam surface 348a on the staple driver 348 engages a cooperating surface 396a on the former bar 396 and rocks the former bar in a clockwise direction, as viewed in FIG. 18, to its staple-forming position. Movement of the former bar in this direction is limited by a stop screw 400 adjustably threaded through a plate 402 on the stitcher and held by a locknut 404. After the staple is formed and as the staple driver starts its inward, staple driving stroke, an inner cam surface 348b engages a cooperating surface 396b of the former bar and rocks the former bar to its staple driving position, as shown in FIG. 19, out of the path of the staple, to permit the staple driver to drive the staple into the work.

WIRE FEEDING

The mechanism for feeding wire to each of the stitchers is shown in FIGS. 11A, 11B, 12, 13, 16 and 17. As best shown in FIG. 12, this mechanism includes knurled feed roller 406 fixed on a shaft 408 rotatably supported in a bearing 410 extending through the upper side plate 326 on the mounting plate 320. Keyed on the opposite end of the shaft is a spur gear 414 which meshes with a pinion 416 fixed on the shaft 322. Thus, during the intervals when the stitcher is being driven, the feed roller 406 is also driven. As shown in FIG. 13, mounted adjacent the feed roller 406 is a pressure roller 418 which is freely rotatable on a bolt 420 projecting from a lever 422 pivotally mounted on a bolt 424 fastened to the plate 326. The lever 422 is urged to rotate in a counterclockwise direction, as viewed in FIG. 13, by a tension spring 426 connected at one end to a screw 428 at the free end of the lever 422 and at its other end to a screw 430 fastened to the plate 326. The spring 426 thus urges the pressure roller toward the feed roller 406 and causes the wire W to be frictionally gripped between them so that the rotation of the feed roller 406 will cause feeding of the wire W to the stitcher. Projecting from the lever 422 is a bar 431 which serves as a handle for rotating the lever 422 in a clockwise direction against the re-

sistance of the spring 426 to separate the rollers for threading the wire W through the mechanism in starting up the machine or replenishing the wire supply.

As may be seen in FIGS. 11A and 11B, the wire W extends from supply spools (not shown) beneath the machine, over one or more sheaves 432 rotatably mounted on a bracket 434 secured to the transverse rail 42, through a tube 436 and a guide bushing 438 supported on a bracket 440 on the side of the plate 326 to the rollers 406 and 418. From these rollers it extends through a curved guide tube 442 which is fixed at one end in a clamp 443 on the plate 326 and at the other end in a block 444 (FIGS. 16 and 17) fastened by screws 446 to the stitcher 68. After emerging from the tube 442 the wire enters a guide block 448 fastened by screws 449 to the stitcher 68, and ultimately reaches a passageway in the stitcher where it is held until it is severed by die surfaces at the inner end of the former 346.

BOX STACKING AND DISCHARGING

As the elevator assembly moves the box to the third and uppermost dwell position, for the third and final staple to be driven into each corner of the box parts, as previously described, the box ends E pass between a pair of pawls 450 (FIGS. 9A and 10) which are pivotally supported at each side of the machine on shafts 452 extending between the flanges of vertical channel members 454 depending from the horizontal channel members 36. The pawls 450 are provided at their inner ends with sharp spurs 450a (FIG. 9A) and are biased by tension springs 456 extending upwardly to screws 458 connected to the channel members 454 so that these spurs 450a project inwardly into the path of the ends of the completed boxes C.

As the boxes C are carried upwardly to the completion of the upward stroke of the elevator assembly, the box ends engage the lower surfaces of the spurs 450a, rocking the pawls upwardly against the resistance of the springs 456. Then as the elevator moves downwardly, the spurs 450a, urged by the springs 456, dig into the box ends and support the box in approximately its uppermost position. During the next box assembly cycle, another completed box is raised by the elevator assembly to the same position, lifting the box above it, and so one, until a vertical stack of completed boxes C accumulates above the bottom box, as shown in FIG. 9A.

As shown in FIGS. 2C and 9A, the top box C in this stack is pushed rearwardly onto an exit plate 460 (FIG. 2C) by rollers 461 at the ends of pusher arms 70 fixed on and extending radially from a shaft 72 rotatably supported in bearings 462 secured on the horizontal angle members 38 at opposite sides of the machine. Also keyed on the shaft 72 is a sprocket 464 about which the aforementioned chain 364 is trained, so that the shaft 72 and pusher arms 70 are driven intermittently, making one revolution during each box-assembly cycle.

To insure that the top box C slides laterally off the top of the stack onto the exit plate 460, rather than being tipped upwardly and tumbling over, a pair of presser shoes 466 are supported at opposite sides of the top of the stack on supporting legs 468 which are pivotally supported on pins 470 (FIG. 2B) received in slots 472a in brackets 472 mounted on the channel members 36 and these presser shoes stand horizontally above the ends of the top box in the stack to resist its upward movement.

MACHINE CONTROL

FIG 24 shows the electrical circuit of the machine. As may be seen in that FIG., the three-phase supply line 474 in connected through a triple-pole single-throw master switch 476 and fuses 478 to a triple-pole single-throw mat feed motor control switch 480 which controls the mat feed motor FIGS. 1 and 9B) and which, as previously mentioned, normally runs continually during operation of the machine.

The supply line 474 is also connected through the master switch 476 and fuses 478 and through the normally open tri-

ple-pole single-throw contacts 482a of a relay 482 to the main drive motor 50. One side of the winding 482b of the relay 482 is connected to one of the three supply lines while the other side is connected through a cam-actuated, normally open, single-pole single-throw switch 484 and through a manually operated, momentary contact, normally open, single-pole, single-throw start switch 485 to another of the three supply lines.

The cam switch 484 is actuated by a cam 488 which, as shown in FIGS. 1 and 20, is fixed on the end of the main drive shaft 82. The cam 488 is provided with a single depression and is so oriented on the shaft 82 that the cam follower roller 490 is in this depression when the elevator assembly is in its lowermost position at the start of the box assembly cycle, thus opening the switch 484.

Wired in parallel with the cam switch 484 is a series of three normally open, single-pole single-throw box-part sensing switches 492 and 494. The two switches 492 are box-end-sensing switches which are mounted, one at each side of the machine, to sense the presence of box ends E in the box end conveying mechanism at each side. One of these switches 492 may be seen in FIGS. 2A and 6, mounted beneath the guide rail 158 with its spring-biased actuating finger 492a extending upwardly and rearwardly to a point where, as shown in FIG. 4, its flattened free end 492b projects upwardly through an opening 158a in the guide rail in such position that a box end resting on the guide rail 158 will depress the finger 492a and close the switch 492. When there are no box ends in the conveying mechanism, the switch is open.

The other switch 494 (FIG. 24) is a normally open, single-pole single-throw mat-sensing switch, which is mounted to be actuated when a mat M is in proper position above the box ends E in the elevator assembly. As shown in FIG. 2C, this switch 494 is supported on a bracket 496 secured to the side rail 34, with its spring-loaded actuating finger 496a projecting upwardly in position to be pressed outwardly by the leading edge of the rear side section R of a mat M as it reaches the far side of the machine, thereby closing the switch 494.

As may be seen in FIG. 24, the relay 482 also includes a pair of normally closed brake control contacts 482c which are connected in series with the brake-control circuit 498 which controls the brake 99 (FIG. 20).

The relay 482 also includes a pair of normally open holding contacts 482d which are part of a series circuit which is connected in parallel with the start switch 485. This series circuit also includes two normally closed single-pole single-throw switches, which are the aforementioned open-gate stop switch 155 (FIGS. 3 and 4) and chain-overload stop switch 117 (FIG. 2B), and a manually operated, normally closed, single-pole single-throw stop switch 500.

As will be understood, closure of the start switch 485 will energize the winding 482b of the relay 482 through the closed contacts of the end-sensing switches 492 and the mat-sensing switch 494, provided there are box ends in the box end conveying mechanism and a mat in position in the elevator assembly. Energization of the winding 482b will close the relay contacts 482a and start the main drive motor 50.

Release of the momentary contact start switch 485 will not break the supply circuit to the winding 482b of the relay 482, which will remain completed through the holding contacts 482d of the relay 482, so long as the open-gate stop switch 155, the chain-overload stop switch 117 and the manual stop switch 500 remain closed. The opening of any of these switches, for example by opening of one of the exit gates 140 of the box end hoppers, by jamming of the box end conveyor chains 48, or by manually depressing the stop switch 500, will break the circuit to the relay winding 482b, opening the contacts 482a to stop the motor 50 and closing the contacts 482c to apply the brake 99 to stop the machine instantly.

The opening of any of the switches 492 or 494, due to the absence of box ends in either of the box end conveyor mechanisms or the absence of a mat in position above the box ends in the elevator assembly will cause the circuit to the relay winding 482b to be broken upon the opening of the cam

switch 484, just prior to the commencement of the upward stroke of the elevator assembly. This cuts off the motor 50 and applies to the brake 99 to stop the machine until the missing parts are supplied and the start switch 485 is again manually actuated.

We claim:

1. A machine for making wirebound boxes comprising a pair of end hoppers for supporting stacks of box ends, a movably mounted carriage assembly, clamp means at each side of said carriage assembly to engage said box ends and hold them in the desired relative positions, box end conveyor means for engaging the bottom box ends in each of said hoppers and moving them into said clamp means while said carriage assembly is in a starting position at one end of its movement, mat-feed means for feeding into the path of said box ends during movement of said carriage assembly a wirebound mat consisting of a bottom section and front and rear side sections foldably attached by a plurality of binding wires secured to said sections by staples driven astride said binding wires and into said box sections carriage drive means for moving said carriage assembly stepwise from said starting position to cause said box ends to engage the inner surface of the bottom section of said mat and move said mat first past a mat-folding station, then to hold said mat and said box ends at a succession of spaced dwell positions in a stapling station, and finally move them to an outfeed station at the opposite end of said movement, mat-folding members at said mat-folding station to engage the front and rear side sections of said mat and fold them around opposed edges of said box ends, stapling mechanisms adjacent the four corners of said stapling station, stapler drive means to actuate said stapling mechanisms in synchronism with the movement of said carriage assembly to drive staples at spaced locations through said front and rear side sections into said opposed edges of said box ends during the successive dwell periods, and box conveyor means at said outfeed station to convey the assembled boxes out of said machine.

2. A machine as described in claim 1 in which said carriage assembly is vertically reciprocable and in which said end hoppers are arranged to support said box ends face to face in a tilted, generally vertical stack, and said box end conveyor means includes box end stripper elements which are movable across the bottom of each stack to engage the bottom box end in said stack and push it endwise out of said hopper, box end turning means to rotate said box ends about their long axes through an angle of roughly 90° to a generally vertical position, and box end pusher elements to engage the generally vertical box ends and push them along guide rails into said clamp means on said carriage assembly.

3. A machine as described in claim 2 in which said box end stripper elements and said box end pusher elements are both mounted on the same pair of endless chains which are driven continually in synchronism with said carriage drive means.

4. A machine as described in claim 1 in which said clamp means are spring biased toward box end clamping position and cam means is provided to open said clamp means automatically for receiving box ends when said carriage assembly is in its starting position at one end of its reciprocal movement and for automatically releasing said clamp means for spring movement to box end clamping position as said carriage assembly moves from said starting position and before said box ends engage said wirebound mat.

5. A machine as described in claim 1 in which said box ends are clamped in such position that in the assembled box they

will be inclined inwardly at their upper ends, wherein the stapling mechanisms at opposite sides of said carriage assembly are mounted for movement toward and away from one another and wherein cam means is provided to cause said stapling mechanisms to move automatically during stepwise movement of said carriage assembly between such successive dwell positions and thus cause each of the several staples to be driven in properly centered relation to the portion of the inclined box end which is opposite the stapling mechanism

10 during the dwell period in which such staple is driven.

6. A machine as described in claim 1 in which said carriage assembly is vertically reciprocable and in which first said box ends and then said wirebound mat are fed onto said carriage assembly while it is in its starting position at the lower end of such reciprocal movement, and wherein pawl means are movably mounted at opposite sides of the upper end of the said reciprocal movement for yielding movement to permit the assembled boxes to be pushed upwardly between said pawl means whereby said pawl means will engage said boxes and hold them in an elevated position after said carriage assembly descends to said starting position for the next cycle.

7. A machine as described in claim 6 in which a box ejector is mounted for movement across the top of a generally vertical column of assembled boxes supported above said pawl means 25 to engage the top box in said column and push it laterally out of the machine.

8. A machine as described in claim 6 in which said mat-feed means includes a generally horizontal supporting platform for supporting said mats, mat-feeding means for engaging a mat 30 supported on said supporting platform, mat feed drive means for actuating said mat-feeding means in synchronism with the movement of said carriage assembly and said box end conveyor means to engage said mat and project said mat across the tops of the box ends in said clamp means, stop means for 35 engaging the leading edge of said mat to arrest movement of said mat and cause it to drop into proper position above said box ends.

9. A machine as described in claim 1 in which said box end conveyor means, said mat feed means, said carriage drive means and said stapler drive means are controlled by a control 40 circuit which includes a box end sensing switch which is actuated only when box ends are available in said box end conveyor means and a mat-sensing switch which is actuated only when a wirebound mat has been fed into the path of said box 45 ends on said carriage assembly, whereby said drive means are effective only when box parts are thus available.

10. A machine as described in claim 9 in which said end hoppers include yieldable exit gates which normally permit one box end to exit at a time from each of said hoppers but 50 which yield to open in the event of a jam of the box ends and wherein said control circuit includes an open-gate switch which is actuated by opening of one of said exit gates to render all of said drive means ineffective.

11. A machine as described in claim 9 wherein said box end conveyor means includes a pair of endless chains with box end-engaging elements fixed thereon at spaced positions and wherein said control circuit includes a chain overload control switch which is actuated to render all said drive means ineffective by movement of a movable chain support member which 55 is yieldable when the tension on one of said chains exceeds a predetermined level encountered in the normal conveyance of box ends thereby.
